INVENTOR:

D. H. Christman

BY *John F. Grenden*

ATTY.

UNITED STATES PATENT OFFICE

DANIEL H. CHRISTMAN, OF SHREVEPORT, LOUISIANA, ASSIGNOR TO CHRISTMAN PROCESS, INCORPORATED, A CORPORATION OF LOUISIANA.

REFLUX CONDENSER.

Application filed February 10, 1923. Serial No. 618,213.

To all whom it may concern:

Be it known that I, DANIEL H. CHRISTMAN, a citizen of the United States, residing at Shreveport, parish of Caddo, State of Louisiana, have invented a certain new and useful Improvement in Reflux Condensers, and declare the following to be a full, clear, and exact description of the same, such as will enable others skilled in the art to which it pertains to make and use the same, reference being had to the accompanying drawing, which forms a part of this specification.

In Patent No. 1,243,384, granted October 16, 1917, there is disclosed a reflux condenser adapted to condense and collect the heavier constituents of the vapors distilled from petroleum and coal tar products. The present invention has for its object to simplify and improve the construction shown in the aforesaid patent.

In the construction of said Patent No. 1,243,384 there are a plurality of pans, arranged one above the other, to catch and grade the condensed fluids, the bottom of the casing or dome serving as still another pan. I have found that it is usually unnecessary to make provision for separating condensed fluids into more than two grades, thus permitting the apparatus to take its most simple form; this resulting in a saving in initial cost and in upkeep. I have further found that the most satisfactory division of the condensed fluids is secured by dividing the casing or dome into two approximately equal parts and providing two deep pans, arranged one above the other, and substantially filling the casing or dome, to collect the fluids condensed in the upper half of the apparatus, while the fluids condensed in the lower half are collected in the bottom of the casing or dome; the two grades of fluids being kept separate until they are discharged from the dome, after which they may be commingled or be led to separate receiving points.

The various features of novelty whereby my invention is characterized will herein-after be pointed out with particularity in the claim; but for a full understanding of my invention and of its objects and advantages, reference may be had to the following detailed description taken in connection with the accompanying drawing, wherein:

Figure 1 is a side elevation of an appa-

ratus arranged in accordance with a preferred form of my invention; and

Fig. 2 is a cylindrical vertical section through such apparatus.

Referring to the drawing, 1 represents a vertical cylindrical casing or dome closed at its ends and separated at the bottom by means of legs 2, or other suitable means. Near the bottom, but at some distance above the lowest point of the latter, is a large vapor inlet or opening 3. At the top is a vapor outlet 4. Within the casing are two deep cylindrical pans 5 and 6, only slightly smaller in diameter than the interior of the casing. The pan 5 is arranged in the upper portion of the casing, and has a depth approximately half as great as the casing. A transverse wall or partition 7 extends across the interior of the casing, a short distance below the bottom of the pan 5. The central portion of the wall or partition is perforated, as indicated at 8, while the surrounding marginal portion is left solid. The pan 6 is similar to the pan 5, but somewhat shallower, and it lies in the casing directly below the partition. The lower pan is made so shallower, so that the bottom thereof will lie above the vapor inlet and will not interfere with the flow of the incoming vapors across the lower end of the casing or dome, whereby the latter are distributed across the entire dome, and rise in contact with the entire area of the cylindrical walls of the dome and of the pans.

From the center of the bottom of the upper pan depends a pipe 9, which conveniently passes down through the transverse partition 7 and opens at its lower end into the interior of the lower pan. A pipe 10 leads from the bottom of the lower pan to the exterior of the dome or casing. The bottom of the dome or casing is provided with a discharge outlet 11 opening out from the lowest point therein.

It will be seen that as the vapors enter the dome they flow across the lower regions thereof in contact with the bottom wall of the dome and the bottom wall of the lower pan, and then rise in the narrow annular passage between the lower pan and cylindrical wall of the casing or dome. The metal surface with which the vapors are thus brought into contact is always cooler than the vapors themselves, and therefore

the heavier ingredients are condensed out of the vapors and flow or drip down into the bottom of the dome, to be finally discharged through the discharge outlet 11. 5 Those vapors that rise to the middle of the dome are caused to flow inwardly from the center of the latter in contact with the under side of the transverse partition and then rise through the perforations in the 10 partition and pass upwardly between the cylindrical seats of the upper pan and the surrounding wall of the casing or dome. Some of the liquid that is condensed on the under side of the partition will flow down 15 along the sides of the dome into the bottom of the latter, while some will drip into the lower pan. All of the condensation formed in the upper half of the dome, that is, above the transverse partition, either flows down 20 and finds its way into the lower pan, or drips into the upper pan from the top wall of the dome. That liquid which drips into the upper pan is discharged into the lower pan, where it mingles with the liquid otherwise collected by the latter, the mixture being 25 discharged through the pipe 10.

It will thus be seen that I have provided a simple and novel construction, in which the dome is divided into two approximately equal parts, the condensation in each of which is kept separate from that in the other and is led to the exterior of the dome independently of the latter. Consequently, while the principle of my invention is the same as that of the aforesaid patent, yet, by the use of two extremely deep pans I am enabled to collect the liquid it condenses in the lower half of the dome in and discharge it at the bottom of the dome, and to collect the liquid that is condensed in the upper half of the dome at a point near the

bottom of the dome, where the discharge for this liquid also takes place. That is to say, the discharge from the upper half of the dome and the discharge from the lower half of the dome both take place near the bottom of the dome, independently of each other.

While I have illustrated and described with particularity only a single preferred form of my invention, I do not desire to be limited to the exact structural details thus illustrated and described; but intend to cover all forms and arrangements which come within the terms employed in the definitions of my invention constituting the appended claim.

I claim:

A reflux condenser comprising a vertical cylindrical dome, a transverse partition extending across the dome at about the middle thereof, the partition having a perforated central portion, a deep pan slightly smaller in diameter than the interior of the dome extending from just above the partition into proximity to the top of the dome, a second deep pan extending from a point somewhat above the bottom of the dome into proximity to said partition, said dome having a vapor inlet between the bottom thereof and the bottom of said second pan and a vapor outlet in the top thereof, the first pan having an outlet leading into the lower pan, and there being outlets leading respectively from the bottom of the lower pan and the bottom of the dome to the exterior of the dome.

In testimony whereof, I sign this specification.

DANIEL H. CHRISTMAN.

Witness:

WILLIAM T. CHRISTMAN.
